UNITED STATES PATENT OFFICE.

THEODORE H. KRUEGER, OF NEW YORK, N. Y.

MACHINE FOR MAKING PAPER PACKAGE-FASTENERS.

1,390,245.

Specification of Letters Patent. Patented Sept. 6, 1921.

Application filed May 31, 1918. Serial No. 301,057.

To all whom it may concern:

Be it known that I, THEODORE H. KRUEGER, a citizen of the United States, residing in the city of New York, county of New York, and State of New York, have invented certain new and useful Improvements in Machines for Making Paper Package-Fasteners, of which the following is a specification.

10 The present invention relates to a machine for manufacturing paper package fasteners of that general character which are disclosed in Patent No. 1,210,952 which was granted to me on January 2, 1917, the
15 object of the invention being to provide a machine of this character which embodies novel features of construction whereby these paper package fasteners can be quickly manufactured in large quantities at a com-
20 paratively small cost.

Further objects of the invention are to provide a machine of this character which is entirely automatic in its operation and discharges the package fasteners in a completed form ready for use, which is not liable to break or get out of repair, and which is practically continuous in its operation, suitable paper strips being unwound from rolls and fed into one end of the machine while the finished package fasteners are discharged from the other end of the machine.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a side elevation of a machine for manufacturing package fasteners which is constructed in accordance with the present invention.

Fig. 2 is a top plan view thereof.

Fig. 3 is a detail view of the cutting mechanism.

50 Fig. 3^a is a detail end view of the cutters and the actuating mechanism therefor.

Fig. 4 is a similar view of the feeding and slitting mechanism.

Fig. 5 is an enlarged top plan view of the assembling mechanism, parts being broken away and shown in section to illustrate more clearly the details of construction.

Fig. 6 is a transverse sectional view on the line 6—6 of Fig. 5, looking in the direction of the arrows, portions being broken away.

Fig. 7 is a similar view on the line 7—7 of Fig. 5, portions being broken away.

Fig. 8 is a side elevation of the construction shown by Fig. 7, looking in the direction of the arrow 8 on Fig. 7, and including the spring clamping elements in addition to the arched hood.

Fig. 9 is a transverse sectional view on the line 9—9 of Fig. 5.

Fig. 10 is a bottom plan view of one of the swinging clamping members which are provided for carrying the slotted elements of the package fasteners.

Fig. 11 is a transverse sectional view through a portion of the assembling mechanism, illustrating the various positions of the trip elements which control the clamping member.

Fig. 12 is a side elevation of the discharge end of the machine, illustrating the mechanism for taking the finished package fasteners from the assembling mechanism and depositing them upon a conveyer belt by means of which they are carried away from the machine.

Fig. 13 is a top plan view of the mechanism illustrated by Fig. 12.

Fig. 14 is a detail view of the swinging clamping jaw and trip arm of the discharge mechanism.

Figs. 15 to 19 inclusive are detail views illustrating the successive movements of the cam actuated parts of the assembly mechanism when the two elements of a package fastener are brought together in an overlapping and interlocking relation.

Figs. 20 and 21 are detail views showing the end cams of the assembling mechanism as developed.

Fig. 22 is a plan view showing the two elements of the package fastener in the end to end position in which they are initially delivered to the assembling mechanism.

Fig. 23 is an edge view of the two elements of the package fastener.

Fig. 24 is a plan view of the finished

package fastener as it is discharged from the machine, the two elements thereof being brought together in an overlapping and interlocking relation.

5 Fig. 25 is a plan view of a portion of the paper blank in the condition in which it is fed to the cutters, the places at which it will be severed by the cutters being indicated by a dot and dash line.

10 Corresponding and like parts are referred to in the following description and indicated in all the views of the drawings by the same reference characters.

The package fasteners which are to be 15 manufactured by this machine are of the general type disclosed in my prior Patent No. 1,210,952 of January 2, 1917, being illustrated by Figs. 22, 23 and 24 of the present drawings. Each package fastener includes

20 two elements A and B, the inner end of each of the elements being reinforced by a second thickness of paper 1 which is secured thereto, while the outer end 2 of each of the elements A and B is provided with a layer 25 of adhesive which is adapted to be moistened when affixing the package fastener to a bundle or package. The element B of the package fastener has the sides thereof notched to provide the laterally projecting

30 wings b, while the element A has the inner end thereof slotted at a to interlock with the said wings b. The package fastener is manufactured and delivered to the consumer with the T-shaped head of the element B overlapping and in an interlocking engagement with the slotted end of the element A, the two elements A and B being thus locked together so that the package fastener can be handled as a unit. The

35 gummed ends 2 of the package fastener can be moistened and the device then applied to a bundle or package in such a manner as to fasten the same, although the two elements of the package fastener are held releasably

40 together so that the bundle or package can be opened for any purpose, such as that of postal inspection, without the necessity of tearing or destroying the fastener. The advantages incident to the use of a package 45 fastener of this kind will be obvious and are set forth in my prior patent in which the package fastener itself is claimed.

The present invention is a machine by means of which these package fasteners can 50 be quickly manufactured in large quantities at a comparatively small cost, the machine being entirely automatic in its operation and requiring but little attention. In Figs. 1 and 2 of the drawings, the numeral 5 designates a table upon which the mechanism is 55 mounted, and it is shown as supported in an elevated position by the legs 6. Arranged under the table is a roll 7 of comparatively narrow ungummed paper, while a roll 8 of 60 wider gummed paper is mounted above the

table. These rolls 7 and 8 are shown as carried by center rods 9 which are received removably in inclined bearing notches 10 opening through the sides of standards 11. Suitable bars 12 are arranged at the ends of 70 the rolls 7 and 8 to maintain them in a properly centered relation to the machine, although both rolls are free to rotate as the paper is unrolled therefrom. The narrow paper strip from the lower roll 7 is carried upwardly around a tensioning roller 13 and then rearwardly into engagement with a pair of cleaning brushes 14. After being 75 acted upon by the brushes 14 the strip passes through the slotted ends of a hanger 15 within which a moistening element 16 is arranged. A brush 17 rests upon the top of the paper strip so as to force it into engagement with the moistening element, said brush being carried by a swinging arm 18 80 and being normally held yieldably in an operative position by a spring 19. Suitable latch means 20 may be provided for holding the brush 17 in an inoperative position when this is necessary for any purpose. 85 The moistening element 16 is shown as resting within a tray 21, into which water is fed from a bottle or reservoir 22 and maintained at a proper level. The moistened narrow strip 7a extends rearwardly from the moistening device around a guide roller 23 which directs it upwardly into engagement with the gummed strip 8a, the latter being drawn rearwardly from the upper roll 8 and passing around a tension roller 24. This tension roller 24 is carried by arms 25 which are pivoted between their ends at 26 and engaged at their lower ends by tension springs 27. In a similar manner the tensioning 90 roller 13 for the narrow strip 7a is carried by arms 28 which are acted upon by tension springs 29. The gummed upper strip 8a and moistened lower strip 7a are brought into contact with each other as they pass between the rear set of pressure rollers 30. 95 The pressure of these rollers can be regulated in the usual manner by means of adjusting screws 31, and the rollers serve to force the narrow moistened strip 7a against the middle portion of the wide gummed strip 8a. From the pressure rollers 30 the two strips 7a and 8a extend forwardly across the top of the table 5, being engaged by a second set of pressure rollers 32 before reaching the stamping and cutting mechanism. These two sets of pressure rollers 30 and 32 will cause the narrow ungummed lower strip 7a which was previously moistened to be securely fastened to the middle 100 of the wide gummed strip 8a, the edges of the wide strip 8a extending laterally upon opposite sides of the narrow strip 7a. The adhesive on these projecting edges of the wide upper strip 8a will not come into contact with the narrow strip 7a and will ac- 105

cordingly not be moistened thereby, but will remain intact to form the gummed end portions 2 of the package fastener.

From the second set of pressure rollers 32 the blank paper strip is carried over the bed 33 of a conventional die press 34. The dies 35 of this press operate upon the paper blank in the conventional manner, serving to form triangular openings for the side notches of the elements B of the package fasteners, and slots for the elements A of the package fasteners. From the punch press 34 the paper blank passes between feed rollers 36 (see Fig. 4) and thence under a conventional printing mechanism P to the cutting blades 37 and 38. The paper blank has an intermittent feed, and each forward movement is for a distance corresponding to the width of one of the package fasteners. A main shaft 39 extends transversely across the top of the punch press 34 and is provided at one end with a pulley 40 by means of which power can be applied thereto. This shaft has a chain and sprocket connection 41 with the printing mechanism P, and is provided with a crank arm 42 having a rack 43 pivotally connected thereto. This rack engages a pinion 44 which is loose upon one of the feed roller shafts 45 and has a pawl and ratchet connection 46 therewith. A roller 47 on a swinging arm 48 is held in a yielding engagement with the back of the rack 43 by means of a spring 49, and it will be obvious that as the main shaft 39 is rotated the rack bar 43 will be reciprocated up and down. Upon the downward movement of the rack bar the pawl and ratchet connection 46 will cause the feed roller shafts 45 and feed rollers 36 to be rotated, thereby feeding the paper blank forward, although upon the upward movement of the rack bar 43 the pawl and ratchet connection 46 will permit the pinion 44 to rotate independently of the feed roller shaft 45. The paper blank will thus be fed forward with an intermittent movement, each forward movement being for a distance equal to the width of a package fastener. While the blank is at rest, between each forward movement thereof, the dies 35 are moved downwardly to stamp the blank, and the printing mechanism P is caused to make an impression upon the blank.

The two feed roller shafts 45 are journaled in a suitable frame 50 mounted upon the table 5, and are geared together at their ends, as indicated at 51, so that the two shafts rotate simultaneously in opposite directions. Mounted upon each of the feed roller shafts 45 between the two feed rollers 36 is a rotary shear or slitter 52, the straight edges of the two cutting disks overlapping and being held in a yielding engagement with each other by means of the springs 53. As the paper blank is advanced

through the feed rollers 36 it is slit longitudinally at the middle point thereof by the beveled edges of the disks 52. A portion of the paper blank as it is fed to the cutters 37 and 38 is illustrated by Fig. 25. The longitudinal slit 54 at the middle of the blank is formed by the cutters 52 as the blank is advanced through the feed rollers 36. The triangular openings 55 at one side of the slit 54 are formed by one of the die elements 35, while the transverse slots a at the opposite side of the longitudinal slit 54 are formed by the other die element. As this blank which is illustrated by Fig. 25 is advanced step by step to the cutters 37 and 38, it is severed transversely upon the dotted lines 56, thereby forming the elements A and B of the package fasteners which are assembled by the mechanism about to be described. The printing mechanism P may leave any desired impression upon the paper blank, such as the legend "Open here," indicated at 57 on Fig. 25.

The upper blade 37 of the cutter is shown as fixed, while the lower blade 38 is pivoted at one end thereof as indicated at 58. The paper blank is carried between the two cutters 37 and 38 and the swinging end of the pivoted cutter 38 is loosely received within the forked end 59^a of an L shaped lever 59, 95 said lever extending rearwardly at one side of the table 5 and being pivotally mounted at an intermediate point as indicated at 60. The rear end of the L-shaped lever 59 extends upwardly and terminates in a shoe 59^b 100 which is positioned to be engaged by a cam 61 on the main shaft 39. At each revolution of the main shaft 39, and after the paper blank has been advanced one step forward, the cam 61 of the main shaft engages the 105 shoe 59^b of the lever 59 and swings the lever to actuate the cutter 38, thereby severing the portion of the blank which was advanced through the cutters and forming one element A and one element B which are 110 complete in every respect and ready to be assembled in an inter-locking relation to form one of the complete package fasteners. The swinging end of the pivoted cutter 38 is formed with a laterally projecting trip 115 arm 62, and the middle portion of the cutter 38 has a pin and slot connection 63 with a lever 64, said lever being pivoted at 65 and provided at its free end with a second trip arm 66. When the swinging cutter 38 is 120 moved upwardly to sever the projecting end of the paper blank the trip arms 62 and 66 are simultaneously moved upwardly and cause the clamps of the assembling mechanism to engage the severed portions of the 125 strip.

The assembling mechanism is mounted upon a transverse shaft 67 and receives an intermittent rotary movement from the main shaft 39. In the present instance there are 130

three complete assembling units mounted upon the shaft 67 and the said shaft 67 is rotated one third of a revolution each time the main shaft 39 makes one complete revolution and delivers a pair of package fastener elements A and B to the assembling mechanism. The element B upon being severed from the main strip by the cutter 38 is clamped against a head 68 by means of a swinging jaw 69 which is automatically released by the trip arm 66 of the cutting mechanism (see Fig. 11). The swinging jaw 69 is rigid with a longitudinal shaft 70 which extends loosely through arms 71 projecting laterally from the clamping head 68 (see Figs. 5 and 8). A coil spring 72 surrounds the longitudinal shaft 70 and normally tends to rotate the same to move the swinging jaw 69 into engagement with the clamping head 68. Rigid with the outer end of the shaft 70 is a bell crank lever 73 which has one end thereof hooked and arranged to interlocked with the hooked end 74^a of a trip lever 74 to lock the swinging jaw 69 in an open and inoperative position. A spring 75 holds the trip lever 74 yieldably in operative position, and one end of the trip lever projects into the path of the trip arm 66 of the cutting mechanism when a particular unit of the assembling device is in position to receive the severed ends of the main blank. When the cutter 38 is actuated the trip arm 62 is moved upwardly and swings the trip lever 74 to disengage the hooked arm 74^a thereof from the bell crank lever 73. The spring 72 then swings the jaw 69 into operative position and causes the element B of the package fastener to be clamped between the clamping head 68 and the swinging jaw 69.

The clamping head 68 is pivotally mounted upon a shaft 76 which projects from a hub 77, said shaft being arranged in a plane at right angles to the axis of the main shaft 67 and on the chord of a circle concentric with the said axis. An arm 78 projects laterally from the pivot end of the clamping head 68 and carries a roller 79 which travels along the edge of a cam ring 80 at the end of the assembling mechanism. A coil spring 81 surrounds the shaft 76 and normally tends to swing the clamping head 68 to hold the roller 79 against the edge of the cam ring 80. This cam ring 80 is rigidly mounted, and it will accordingly be obvious that the movement of the roller 79 along the high, low, and inclined portions of the cam ring will result in swinging the clamping head 68 and jaw into different positions, although the element B will remain tightly gripped until the finished package fastener is ready to be discharged from the machine.

Referring again to Fig. 11 of the drawing, the package fastener element after being clamped will be carried downwardly and

forwardly in the direction of the arrows. When the particular clamp of the assembling mechanism has completed two-thirds of a revolution the assembling operation will be finished and the hooked arm of the bell crank lever 73 will engage a fixed pin 82 projecting from one end of the machine, thereby moving the swinging jaw 79 into an open position and releasing the element B carried thereby. This results in bringing the other arm of the bell crank lever 73 into position for engagement by a second fixed pin 83 which cooperates therewith to bring all of the parts of the clamping mechanism back into their original position, the swinging jaw 69 being locked in an open position by the engagement of the hooked end of the bell crank 73 with the hooked end 74^a of the trip lever 74. The mechanism is now in position to receive another element B exactly as in the previous instance.

The element A of the package fastener is simultaneously gripped by a somewhat similar mechanism (see Figs. 5, 6 and 10 of the drawing). When the cutter 38 is actuated the trip arm 66 engages a trip lever 84 which is pivoted at 85 and has a hooked end 84^a for engagement with the hooked end of a bell crank lever 86. This bell crank lever is rigid with a shaft 87 which is arranged parallel to the main shaft 67 and is journaled in one side of the clamping head 88. The swinging jaw 89 is rigid with the shaft 87, and a coil spring 90 which surrounds the shaft normally tends to move the swinging jaw into operative position. As soon as the trip arm 66 is moved upwardly and trips the lever 84 the jaw 89 is released and swings into operative position, gripping the element A of the package fastener and holding it against the clamping head 88. This clamping head is pivotally mounted at 91 upon a pair of arms 92 which are in turn pivotally mounted at 93 upon wings 94 projecting from a hub 95 on the main shaft 67. These arms 92 have the general direction of the chord of a circle concentric with the main shaft 67, and the two sets of pivots 91 and 93 are both arranged in lines parallel to the axis of the main shaft 67, so that the clamping head 88 can be bodily moved back and forth in a direction parallel to the axis of the shaft. The bell crank lever 86 of these clamps for the elements A of the package fasteners cooperate with fixed pins 82 and 83, exactly as in the previous instance, to release the assembled package fastener and return the swinging jaws and trip elements to their original positions before the unit has been rotated one complete revolution and brought into position to again receive a package fastener element A.

A rigid cam ring 96 is arranged at the opposite end of the assembling device and a shoe 97 at one end of the clamping head 130

88 travels upon the cam and cooperates therewith to move the clamping head back and forth in a direction parallel to the axis of the main shaft 67. A suitable spring is 5 provided for normally holding the shoe 97 in a yielding engagement with the cam 96.

The two elements A and B of the package fastener are thus simultaneously gripped by the two clamps of an assembling unit as 10 they are severed by the cutter 38. As the assembling unit is bodily rotated with the main shaft 67, the roller 79 travels into a low portion of the cam ring 80 and thereby swings the clamping head bodily upon the 15 shaft 76 and brings the T-shaped head of the element B into an arched hood 98 carried by an arm 99 projecting from a hub 100 upon the main shaft 67 (see Figs. 7 and 8). This results in flexing the lateral arms 20 of the T-shaped head of the element B so that the arms extend at substantially right angles to the body portion of the element B. This position is indicated by Fig. 16. The position of the elements A and B when 25 first engaged by the clamp is indicated by Fig. 15. While the element B is held in this position the clamping head 88 carrying the element A is moved longitudinally into a position opposite the hood 98. This 30 position is indicated by Fig. 17 and is brought about by the shoe 97 riding upon a raised portion 96^a of the cam 96. The slots *a* of the element A are now directly 35 opposite the bent ends of the T-shaped head 5 of the element B, so that when the clamping head 68 is again swung back into its original position the T-shaped head of the element B will be interlocked with the slots *a* of the element A, this position of the parts 40 being indicated by Fig. 18. The two elements A and B are now completely assembled, and after the element B is released by the jaw 69 the complete package fastener is carried by the clamping head 88 as 45 the same moves back to its original position, this being indicated by Fig. 19.

The cam rings 96 and 80 are illustrated by Figs. 20 and 21 in a developed form, the clamps or holders moving along the sides 50 of the respective cams in the direction indicated by the arrows. When the elements A and B of the fastener are initially gripped the roller 79 of the clamping member 68 is at that portion of the cam ring 80 corresponding to the left hand end of Fig. 21, 55 while the shoe 97 of the other clamping member or holder 88 is at the portion of the cam ring 96 corresponding to the left hand end of Fig. 20. As the carrier upon 60 which the assembling devices are mounted is rotated the shoe 97 travels along a low and straight portion 96^b of the cam ring 96 and the element A of the fastener is thus maintained in the same relation to the element B. At the same time the roller 79

travels over an inclined portion 80^a of the cam 80 and thereby bodily swings the clamping head 68 into the arched hood 98, with the result that the lateral arms of the T-shaped head of the fastener element B are 70 flexed into a position at substantially right angles to the body portion of the element, this position of the parts being indicated by Fig. 16. Upon a further movement of the rotary carrier the roller 79 travels over a 75 low and straight portion 80^b of the cam 80, with the result that the fastener element B is held in an unchanged position. During this period of time the shoe 97 of the other holder or clamp travels upon an inclined 80 portion 96^c of the cam 96 and thereby moves the clamping head 88 in a direction parallel to the axis of the main shaft 67, bringing the slotted end of the fastener element A opposite the open side of the hood with 85 the slots *a* thereof in alignment with the flexed wings of the T-shaped head of the element B. This position is illustrated by Fig. 17. Upon a further movement of the rotary carrier the roller 79 travels over an 90 inclined portion 80^c of the cam 80 and thereby swings the clamp 68 back toward its original position, with the result that the flexed lateral arms of the T-shaped head of the element B penetrate the slots *a* of the 95 element A, the said element A being held in an unchanged position by the travel of the shoe 97 over the straight and raised portion 96^a of the cam ring 96. The fixed trip pin 82 now releases the jaw 69 of the 100 holder or clamp 68, and the roller 79 travels along an intermediate straight portion 80^d of the cam 80, while the shoe 97 travels along an inclined portion 96^d of the cam 96 and retracts the carrier or holder 88 to its 105 original position, the jaw 89 being tripped to release the assembled package fastener which is gripped by a discharge device and deposited upon an endless carrier by means of which it is conveyed away from the machine. 110 The roller 79 travels over a third inclined portion 80^e of the cam 80 to a straight raised portion 80^f thereof which brings the parts into their original position. During this final stage of the movement the shoe 97 115 travels over a low portion 90^e of the cam 96 which is really a continuation of the low portion 90^b. When the ends of the two cams are reached one cycle of operation is completed and the device is ready to receive another pair of fastener elements A and B and start upon another cycle of operation. 120

The mechanism for discharging the assembled package fasteners from the machine is illustrated by Figs. 12 and 13. The main 125 shaft 39 of the machine is provided with an eccentric 101 which is surrounded by a ring 102 from which a reciprocating arm 103 projects. This arm is pivotally connected at 104 to a plate 105 which is loosely mounted 130

on one end of the shaft 67. A pawl 106 which is carried by this plate is mounted for engagement with a notched disk 107 on the shaft 67. There are three notches in the 5 periphery of the disk 107, and each oscillation of the plate 105 upon the shaft 67 as a center results in rotating the notched disk 107 and shaft 67 exactly one-third of a revolution. It will be recalled that there are 10 three sets of assembling units carried by the shaft 67, so that each one-third of a revolution caused by the oscillation of the plate 105 will bring one unit of assembling elements into proper position to receive the fastener 15 elements A and B which are severed from the end of the paper blank by means of the cutter 38. A pawl 108 is provided for engagement with the notched disk 107 to prevent over-throw or too great a movement 20 thereof. A tension spring 109 normally tends to swing the pawl into an inoperative position, while a tail piece 110 at the pivot end of the pawl is engaged by a finger 111 on the plate 105 to swing the pawl 106 into operative 25 position when the plate has reached the limit of its oscillatory motion. The pawl 108 is thus caused to engage one of the notches of the disk 107 at the proper time to lock the disk against further rotation and 30 prevent over-throw thereof.

A lateral arm 112 projects from the plate 105 and is connected by a link 113 to an arm 114 which is rigid with a transverse shaft 115. The intermediate portion of this shaft 35 115 is provided with a pair of L-shaped arms 116 which are connected at their extremities by a transverse rod 117 extending parallel to the shaft. This rod is provided with a fixed jaw 118 and also with a movable jaw 119, 40 the latter jaw being formed at the pivot end thereof with an upwardly extending trip arm 120. When the transverse shaft 115 is rotated to swing the elements thereof toward the machine, the two jaws 118 and 119 receive 45 one of the assembled package fasteners from the assembling mechanism and the said jaws are forced into a closed position and caused to grip the package fastener by the engagement of the trip arm 120 with a stop 50 121. Upon rotation of the transverse shaft 115 in the opposite direction the trip arm 120 is brought into engagement with a second stop 122 which moves the jaw 119 of the clamping device into an open position and 55 releases the package fastener. The package fastener then drops upon an endless belt 123 by means of which it is conveyed away from the machine, said belt passing around a roller 124 which receives an intermittent 60 movement from the mechanism of the machine. A ratchet wheel 125 is rigid with the shaft 126 of the roller, and is engaged by a pawl 127 on a lever 128 which is loose upon the said shaft 126. A pin 129 at the end of 65 this lever 128 is received within a forked

rear extension 114^a of the arm 114. It will thus be obvious that as this arm is oscillated the lever 128 will be swung back and forth and the roller 124 given an intermittent movement by the action of the pawl and ratchet mechanism. The discharge mechanism is thus driven in perfect synchronism with the cutting and assembling mechanism so that the operation of the machine is continuous and automatic from start to finish. 70 75

Some means is preferably provided for locking the movable jaw 119 of the discharge clamping device in either an open or a closed position. For this purpose the two jaws 118 and 119 are shown as provided at their rear ends with the respective extensions 118^a and 119^a, the inner face of one of the extensions being provided with a resilient projection or head 130 which frictionally engages the other extension and thereby holds the jaws in either an open or a closed position, although the position of the movable jaw 119 can be readily shifted when the trip arm 120 thereof engages the stop 120 or 121. 80 85

In the particular embodiment of the invention which has been illustrated and described for illustrative purposes, the element B of the package fastener is shown as having a substantially T-shaped formation. It will be understood, however, that this is not at 90 all essential to the invention, since the mechanism could be used for manufacturing and assembling package fasteners of this general character of many different forms and shapes, one of the elements of the package 100 fastener having a tongued head which interlocks with slots in the other element of the package fastener. It is entirely within the spirit of the invention to use the device for the manufacture of any device such as a 105 package fastener comprising two elements which have a detachable and interlocking tongue and slot connection with each other. 110

In a machine of this character there is an important advantage derived from the use 110 of the multiple head assembler. With this construction the other parts of the machine can run faster without causing the several strips from piling up in the assembler. It requires four or five consecutive motions to 115 assemble a package fastener of this character, and if there were only one assembling unit, these four or five motions would all have to be completed before the next set of severed strips could be fed into the assembler. By providing a plurality of assembling heads on a rotating drum, each set of severed strips is immediately moved out of the way and the actual assembling accomplished while other sets of severed strips 120 are fed to the other assembling heads. 125

Another important feature of the invention is that the reinforcing thickness is fed into the machine in the form of a continuous strip. This obviates the necessity of rein- 130

forcing the gummed sheet in spots and simplifies and cheapens the cost of manufacture. The reinforcing strip may be of a comparatively stiff material, while the 5 gummed strip is of a comparatively soft and pliable material so that it will conform to an irregular surface and be susceptible of being securely fastened thereto by the adhesive. 10 Certain of the principles of my invention find useful employment without using the particular assembling means illustrated and described; that is to say—so much of my invention as relates to the novel method of 15 forming reinforced elements for paper package fasteners may be employed while other and different means than that described could be employed for detachably connecting the complementary or component parts of 20 each fastener together. Therefor, I desire to be understood as covering the novel features and principles of my invention in any manner in which they may be jointly or severally usefully employed. Where I have 25 used the word "paper" in the foregoing specification and annexed claims, I do so in a broad sense, since obviously the package fasteners may be made of other material, such as cloth or the like. I, therefore, wish 30 to be understood as covering such other substitute material, or a combination of paper and other dissimilar material.

No claim is made to the method of making paper package fasteners hereinabove described, as said method is claimed in my copending application, Serial No. 427,483, filed Dec. 1, 1920, constituting a division of the present application.

Having thus described the invention, what 40 I claim as new and desire to secure by Letters Patent, is:—

1. A machine of the character described including a frame, supporting means thereon for rolled strips of sheet material, pressure 45 rollers, guide means for directing the strips from the supply rolls to the pressure rollers, means for treating one of the strips to cause the strips to stick together after passing through the pressure rollers, means 50 for advancing the strips, and means for cutting off successive lengths of the strips, and means for detachably uniting said successive lengths of the strips to form complementary fastener elements.

55 2. A machine of the character described, including a frame, supporting means thereon for two supply rolls of narrow sheet material, pressure rollers, guide means for directing the strips from the supply rolls to the pressure rollers, means for treating one of the strips to cause the two strips to stick together, means for advancing the strips, means for severing successive lengths of the strips, and die means for punching 60 the strips during their movement through

the machine so that the severed portions thereof constitute complementary elements adapted to be assembled in an interlocking relation.

3. A machine of the character described, 70 including a frame, supporting means thereon for two supply rolls of narrow sheet material, pressure rollers receiving the strips from the supply rolls, means for treating one of the strips so that the two strips 75 will stick together, means for advancing the strips, means for longitudinally slitting the strips, means for severing successive lengths of the slit strip, and die means for punching the strip during its passage through the 80 machine so that the severed end portions thereof can be brought together in an interlocking relation.

4. A machine of the character described, 85 including a frame, supporting means thereon for two supply rolls of narrow sheet material, pressure rollers receiving the strips from the supply rolls, means for treating one of the strips to cause the two strips to stick together, feed rollers for advancing the 90 strips through the machine, rotary cutters rigid with the feed rollers for longitudinally slitting the strips, means for severing successive lengths of the slit strips, and die means for punching the strips so that the severed 95 portions thereof can be brought together and assembled in an interlocking relation.

5. A machine of the character described, 100 including a frame, supporting means thereon for two supply rolls of narrow sheet material, pressure rollers receiving the strips from the supply rolls, means for treating one of the strips to cause the two strips to stick together, feed rollers for advancing the strips through the machine, shafts carrying 105 the feed rollers, coöperating cutting disks mounted upon the shafts and longitudinally slitting the strips, means for intermittently rotating the feed rollers, and transverse cutters for severing successive lengths of the 110 slit strips, and die means operating upon the strips during the period of rest between the intermittent movements thereof so that the severed portions of the strips can be assembled in an interlocking relation.

6. A machine of the character described, 115 including a frame, supporting means thereon for supply rolls of comparatively wide and narrow sheet material, pressure rollers, means for directing the strips of sheet material to the pressure rollers with the narrow strip at the middle of the wide strip, means for treating one of the strips to cause the two strips to stick together, means for advancing the strips through the machine, 120 means for longitudinally slitting the strips, a transverse cutter for severing successive length of the strips, and die means operating upon the strips to form sets of parallel slots on one side of the slit, the transverse 125 130

cutter operating between the sets of slots and intersecting the spaced openings, so that one of the severed elements has a T-shaped head adapted to be brought into an interlocking connection with the slots of the other severed element.

7. A machine of the character described, including a frame, supporting means thereon for two supply rolls of sheet material, 10 one strip of material being comparatively wide while the other strip is comparatively narrow, pressure rollers, means for directing the strips to the pressure rollers with the narrow strip at the middle of the wide strip, 15 means for treating one of the strips to cause the two strips to stick together, feed rolleres, coöperating cutter disks actuated by the feed rollers to slit the strips longitudinally, a main drive shaft, means actuated by the 20 main drive shaft for intermittently moving the feed rollers, a transverse cutter for severing successive lengths of the slit strips, a die for punching the strips so that the severed elements can be assembled in an interlocking relation, and means for operating the die and transverse cutter from the main shaft in synchronism with the feed rollers.

8. A machine of the character described, including a frame, means for supplying a 30 strip of sheet material thereto, means for advancing the strip of sheet material through the machine, means for slitting the strip longitudinally as it passes through the machine, a transverse cutter for severing successive lengths of the slit strip, and a die 35 for punching the strip as it passes through the machine so that the severed elements are adapted to be assembled in an interlocking relation.

40 9. A machine of the character described, including means for simultaneously forming separate and complemental fastener elements which are adapted to have an interlocking connection with each other, and mechanical 45 means receiving the separate fastener elements and automatically bringing them into an interlocking relation and discharging them as a unit.

10. A machine of the character described, 50 including means for simultaneously forming separate and complemental fastener elements, one of which is slotted and the other of which has a T-shaped head, and mechanical means receiving the separate fastener elements and automatically bringing the T-shaped head of the second mentioned element into an interlocking engagement with the slots of the first mentioned element, the two elements being discharged as a unit in an interlocked relation.

11. A machine of the character described, 55 including means for supplying a strip of sheet material thereto, means for advancing the strip, means for slitting the strip longitudinally, a transverse cutter for severing

successive lengths of the strip, die means for punching the strip so that the severed elements are adapted to have an interlocking connection with each other, and mechanical means receiving the severed elements and 70 automatically bringing them into an interlocking relation, said elements being discharged as a unit in an interlocked condition.

12. A machine of the character described, 75 including strip advancing means, a transverse cutter for severing successive lengths of the strip, means acting upon the strip previous to the action of the cutter for longitudinally slitting the same so that the severed portion is in two elements adapted 80 to have an interlocking connection with each other, and mechanical means receiving the elements and automatically assembling the same, the elements being discharged as a unit in an interlocking relation.

13. A machine of the character described, 85 including means for simultaneously forming and delivering complemental fastener elements which have an end to end relation and are adapted to be overlapped and interlocked, mechanical means receiving the separate fastener elements and automatically moving the ends thereof into an overlapping relation and causing the elements to interlock, the elements being discharged as 90 a unit in an interlocked condition.

14. A machine of the character described, including separate holders, means for delivering complemental fastener elements to the respective holders, means for advancing the 100 holders, and means for automatically actuating the holders and coöperating therewith as they are advanced to bring the fastener elements into an interlocking connection.

15. A machine of the character described, 105 including separate holders, means for delivering complemental fastener elements to the respective holders, means for advancing the holders, cams extending along the paths of the holders, and means actuated by the 110 cams and coöperating with the holders to bring the fastener elements into an interlocking connection as the holders are advanced.

16. A machine of the character described, 115 including a rotary carrier, separate clamps mounted upon the rotary carrier, means for delivering complemental fastener elements to the respective clamps, and means actuated by the movement of the carrier and 120 coöperating with the clamps for automatically manipulating the fastener elements to bring the same into an interlocking connection.

17. A machine of the character described, 125 including a rotary carrier, a pair of independent clamps mounted upon the carrier, means for delivering complemental fastener elements to the clamps, a cam ring at each end of the rotary carrier, and means con- 130

trolled by the cam rings and coöperating with the clamps to automatically manipulate the fastener elements and bring the same into an interlocking connection with each other.

18. A machine of the character described, including a rotary carrier, independent clamps thereon, means for delivering complementary fastener elements to the respective 10 clamps, one element being slotted while the other element has a tongued head, and means for automatically actuating the clamps and coöperating therewith to flex the wings of the tongued head of one element and bring them into an interlocking 15 engagement with the slots of the other elements as the carrier is rotated, the two elements being discharged as a unit in an interlocked relation.
19. A machine of the character described, including a carrier, a pair of independent holders thereon, means for delivering complementary fastener elements to the holders, one element being slotted while the other 25 element has a tongued head, means actuated by the advance of the carrier to flex the wings of the tongued head of the second element, means actuated by the advance of the carrier to move the first element into 30 position with the slots thereof opposite the flexed tongue of the second element, and means for further moving the second element toward the first element to pass the flexed tongue thereof through the slots of 35 the first element, the two elements being discharged from the machine as a unit in an assembled relation.

20. A machine of the character described, including a rotary carrier, independent holders thereon for receiving complementary fastener elements, one element being slotted while the other element has a tongued head, cams at the ends of the rotary carrier, means controlled by one of the cams to flex the 45 wings of the tongued head of the second element, means controlled by the other cam for moving the first element into position with the slots thereof opposite the flexed wings of the second element, and means controlled by the first cam for moving the second element toward the first element and passing the flexed arms through the slots of the second element, the two elements being discharged as a unit in an interlocked 50 condition.

21. A machine of the character described, including a rotary carrier, a pair of separate holders mounted thereon, means for delivering complementary fastener elements to the holders, said elements being initially in 60 an end to end relation and one of the elements being slotted while the other element has a tongued head, means actuated by the advance of the carrier to flex the wings of the tongued head of the second element, and

means actuated by the further advance of the carrier to move the first element bodily into an overlapping relation with respect to the second element and with the slots thereof in registry with the flexed wings of the second element, said second mentioned means being actuated by the still further movement of the carrier for moving the second element toward the first element to pass the flexed wings through the slots of the second element, the two elements being discharged from the machine as a unit in an interlocked condition. 70

22. A machine of the character described, including a rotary carrier, a pair of separate holders adjustably mounted upon the carrier, means for delivering complementary fastener elements to the holders, said fastener elements being initially in an end to end relation and one of the elements being slotted while the other element has a tongued head, an arched hood upon the carrier, means actuated by the advance of the carrier to move one of the holders and bring the tongued head of the second element into the arched hood, so as to flex the wings of the tongued head, and means actuated by a further advance of the carrier to move the other holder bodily and bring the slotted end of the first element opposite the arched hood with the slots thereof in alignment with the flexed wings of the second element, said second mentioned means being actuated by a still further movement of the carrier to move the first holder back toward its original position and cause the flexed wings of the second element to enter the slots of the first element, the two elements being discharged from the machine as a unit in an interlocked relation. 80

23. A machine of the character described, including a rotary carrier, a pair of separate clamps movably mounted thereon, means for delivering complementary fastener elements to the clamps, one element being slotted while the other element has a tongued head, and the elements being initially engaged in an end to end relation, a cam at each end of the rotary carrier, an arched hood upon the carrier, means actuated by one of the cams to swing one of the clamps and bring the tongued head of the second element into the arched hood so as to flex the lateral wings of the tongued head, and means actuated by the other cam for bodily moving the other clamp in a direction parallel to the axis of the carrier to bring the first element in an overlapping relation to the second element with the slots thereof in alignment with the flexed wings of the tongued head, said second mentioned means being actuated by the first cam on the further movement of the carrier to swing the first clamp away from the arched hood and cause the flexed wings of the 110 115 120 125 130

- tongued head of the second element to enter the slots of the first element, the two elements being discharged from the machine as a unit in an interlocked relation.
- 5 24. A machine of the character described, including a rotary carrier, a pair of independent clamps movably mounted thereon, one of the clamps being mounted to move bodily in a direction parallel to the axis 10 of the carrier while the other clamp has a transverse swinging movement, means for delivering complementary fastener elements to the clamps, one element being slotted while the other element has a tongued head, 15 said elements being initially in an end to end relation and the first element being engaged by the first clamp while the second element is engaged by the second clamp, cams at opposite ends of the carrier, an arched hood 20 mounted upon the carrier, means actuated by one cam to swing the second clamp and bring the second fastener element into the arched hood with the wings of the tongued head thereof flexed, and means actuated by 25 the other cam for subsequently moving the first clamp and bringing the first fastener element into an overlapping relation with the second element with the slots thereof in registry with the flexed wings of the second element, said second mentioned means 30 being subsequently actuated by the first mentioned cam to swing the second clamp back to its original position and cause the flexed arms of the tongued head of the second element to enter the slots of the first element, the two elements being discharged 35 from the machine as a unit in an interlocked relation.
25. A machine of the character described, 40 including a rotary carrier, a pair of separate spring actuated clamps mounted upon the carrier, feed means for delivering complementary fastener elements to the clamps, said elements being constructed to have an 45 interlocking relation with each other, trip means for causing the clamps to engage the elements, means actuated by the forward movement of the carrier to manipulate the clamps and coöperate therewith to bring 50 the complementary fastener elements into an interlocking relation, and means for releasing the fastener elements and resetting the spring clamps, the fastener elements being discharged as a unit in an interlocked 55 relation.
26. A machine of the character described, 60 including a rotary carrier, a pair of spring clamps thereon, trip levers for locking the clamps in an open position, means for delivering complementary fastener elements to the open clamps, said elements being formed to have an interlocking engagement with each other, trip means for actuating the trip levers to release the clamps and cause them 65 to grip the fastener elements, means actuated by the forward movement of the carrier to manipulate the clamps and coöperate therewith to bring the fastener elements into an interlocking relation, and means for releasing the fastener elements and resetting the spring clamps, the fastener elements being discharged as a unit in an interlocked relation.
27. A machine of the character described, 70 including strip supply means, means for advancing the strip, a transverse cutter for severing successive lengths of the strip, means for longitudinally slitting the strip prior to the action of the cutter so that the severed portion will constitute complementary fastener elements adapted to have an interlocking relation, a rotary carrier, a pair of spring clamps mounted upon the carrier, trip levers for holding the spring clamps in an open position, means actuated by the forward movement of the carrier to manipulate the clamps and coöperate therewith to bring the fastener elements into an interlocking relation, and means for discharging the fastener elements and resetting the spring clamps and trip levers, the fastener elements being discharged as a unit in an assembled relation.
28. A machine of the character described, 80 including means for simultaneously forming separate and complementary fastener elements which are adapted to have an interlocking connection with each other, assembling means receiving the said separate fastener elements and automatically bringing them into an interlocking relation, and discharge means receiving the assembled fasteners from the assembly means.
29. A machine of the character described, 85 including a rotary carrier, independent holding means upon the carrier, means for delivering complementary fastener elements to the holding means, means actuated by the forward movement of the carrier to manipulate the holding means and coöperate therewith to bring the fastener elements into an 90 interlocking relation, a swinging frame movable toward and away from the carrier, gripping means on the swinging frame for engaging the assembled fastener elements, and means for causing the gripping element to engage the fastener element when swung toward the carrier and to release the same when swung away from the carrier.
30. A machine of the character described, 95 including a rotary carrier, independent holding means on the carrier, means for delivering complementary fastener elements to the holding means, means actuated by the forward movement of the carrier to manipulate the holding means and coöperate there- 100

- with to assemble the fastener elements in an interlocking relation, a swinging frame movable toward and away from the carrier, gripping means on the frame, means for rendering the gripping means operative when the frame is swung toward the carrier and inoperative when swung away from the carrier, and means for operating the carrier and swinging the frame in synchronism with each other.
31. A machine of the character described, including strip feeding means, a cutter for severing successive lengths of the strip, means for longitudinally slitting the strip previous to the action of the cutter so that the severed portion thereof will constitute complementary fastener elements adapted to interlock with each other, a rotary carrier, means upon the carrier for gripping the fastener elements and bringing them into an interlocking relation, discharge means receiving the assembled fastener elements and depositing them away from the carrier, a drive shaft, means operated by the drive shaft for advancing the strip, operating the cutter, rotating the carrier and moving the discharge means in synchronism.
32. A machine of the character described, including strip feeding means, a cutter for severing successive lengths of the strip, means for longitudinally slitting the strip prior to the action of the cutter so that the severed portion thereof will constitute complementary fastener elements formed respectively with tongues and slots adapted to interlock with each other, a carrier, and means upon the carrier for gripping the complementary fastener elements and bringing the tongues of one of the elements into engagement with the slots of the other element.
33. A machine of the character described, including strip feed means, a cutter for severing successive lengths of the strip, means for longitudinally slitting the strip prior to the action of the cutter so that the severed portion thereof will constitute complementary fastener elements formed respectively with tongues and slots adapted to interlock with each other, means for gripping the fastener elements and moving the same into an overlapping relation, means for flexing the tongues of one of the fastener elements and holding the flexed tongues in alignment with the slots of the other fastener element, and means for bringing the elements together and causing the flexed tongues to pass through the slots.
34. A machine of the character described, including strip feeding means, a cutter for serving successive lengths of the strips, means for longitudinally slitting the strip serving successive lengths of the strip prior to the action of the cutter so that the severed fastener thereof will constitute complementary fastener elements provided
- respectively with tongues and slots adapted to interlock with each other, a carrier, means upon the carrier for gripping the fastener elements and moving them into a spaced and overlapping relation, means for flexing the tongues of one of the fastener elements and holding the tongues in alignment with the slots of the other fastener element, and means for moving the fastener elements together and permitting the flexed tongues of one element to enter the slots of the other element.
35. A device for assembling complementary fastener elements formed respectively with tongues and slots which are adapted to interlock with each other, including means for gripping the elements and moving them into a spaced and overlapping relation, means for flexing the tongues of one of the elements and holding the tongues in registry with the slots of the other element, and means for bringing the elements together and permitting the flexed tongues to enter the slots.
36. A device for assembling complementary fastener elements formed respectively with tongues and slots which are adapted to interlock with each other, said elements being delivered to the device with the ends thereof abutting substantially against each other, means for gripping the fastener elements and moving the initially abutting ends thereof into a spaced and overlapping relation, means for flexing the tongues of one of the elements and holding the tongues in registry with the slots, and means for moving the fastener elements together and permitting the tongues to enter the slots.
37. In a machine of the character described, means for successively forming separate and complementary fastener elements and means including a device acting upon the fastener elements for detachably uniting them in pairs to form paper package fastener units.
38. In a machine of the character described, the combination of means for simultaneously forming separate and complementary fastener elements from reinforced paper and mechanical means for receiving separate fastener elements and detachably uniting the reinforced portions of pairs of said elements to form paper package fastener units.
39. In a machine of the character described, the combination of means for supporting rolled strips of material, means for uniting the material of different widths to form a reinforced strip, pressure rolls for uniting said strips, means acting upon the reinforced strip to successively form therefrom, complementary fastener elements detachably secured together in pairs to form complete package fastener units.

40. In a machine of the character described, the combination of means for supporting a rolled strip of material, having gum applied to one surface thereof, and a rolled strip of ungummed material, moistening means acting upon one of such strips, pressure rollers for uniting the ungummed strip and the gummed strip, means for intermittently advancing the united strip thus formed and means for intermittently forming from said strip complementary, detachably united fastener elements,

each detachably united pair of such elements forming a complete paper package fastener.

15

41. In a machine of the character described, the combination of means for supporting rolled strips of material, means for uniting the strips to form reinforced stock, means for advancing the united strip thus formed intermittently and means for forming successively therefrom complementary fastener elements.

THEODORE H. KRUEGER.
